MAURICE P. SULLIVAN, OF NEW YORK, N. Y., ASSIGNOR TO SPLITDORF ELECTRICAL COMPANY, OF NEWARK, NEW JERSEY.

SPARK-PLUG.

1,281,429.

Specification of Letters Patent. Patented Oct. 15, 1918.

Application filed March 1, 1917. Serial No. 152,826.

To all whom it may concern:

Be it known that I, MAURICE P. SULLIVAN, a citizen of the United States, residing at New York, in the county and State of New York, have invented certain new and useful 5 Improvements in Spark-Plugs, of which the following is a specification.

This invention relates to spark plugs and comprises means whereby high tension electric currents, generated by any suitable 10 method are caused to produce in a highly efficient and desirable manner ignition sparks for the purpose of firing the explosive charges in the cylinders of internal combustion 15 motors.

One of the objects is to produce a plug in which the insulating member is protected from the severe heating influence of the exploding gases.

20 Another object is the provision of means to accommodate the discharge of the hot gases, and also means whereby the heat is readily conducted to the exterior parts of the plug and there dissipated, rather than being 25 concentrated on the interior with the result of unduly heating the central electrode and insulating element.

Another object is to obtain a plug which, together with the above qualities, is further 30 characterized as one wherein the electrode terminals extend well into the region of the live cylinder gases, thereby giving a more certain and effective action of the ignition spark.

35 These and other objects will become better understood after having pursued the following description, together with the accompanying drawing which constitutes a part of this specification. With reference to said 40 drawing, wherein like characters identify corresponding parts in each of the figures:

Figure 1 is a combined side elevation and longitudinal section of an assembled spark plug having embodied therein the features 45 of my invention.

Fig. 2 is an end elevation of the plug looking as from the bottom.

Considering the drawing in particular 1 is the body or shell of the plug constructed 50 preferably of steel. Said shell terminates at one end in a nose portion 2 which for reasons to be explained hereinafter is of a comparative thick and heavy formation. The nose 2 is exteriorly threaded as at 3 to permit of its application to the orifice provided

in the combustion cylinder. A shoulder 4 at the junction of the nose 2 with the intermediate portion of the shell, and which may be supplied with a gasket, serves to seat against the surface of the said cylinder to 60 insure a leak-proof joint. The upper end of said shell is preferably somewhat larger in cross-section than the intermediate portion 1 and has its peripheral contour in the nature of a hexagon or other suitable shape in order 65 to accommodate a wrench for screwing the shell in position. As seen in Fig. 1 this upper end is slotted at 5 to any convenient depth thereby giving a series of fins 6 integral with the body of the plug. Said fins 70 may be of any desirable number, their object being to present a large surface area. The shell 1 has an interior longitudinal recess 7 which extends to a point substantially opposite shoulder 4. However it is not imperative 75 that these parts be thus exactly related. Extending through the nose 2 to communicate with the recess 7 is a cylindrical recess which comprises the reduced section 8 and the still further reduced section 9. Said hollow section 80 9 has its lower end provided with a circular groove into which a ring 10 is fitted. Ring 10 is made of round stock, preferably of a special alloy material, and serves as the terminal for the ground electrode. A plurality of circular passages 11, radially spaced about central recess 9, extend longitudinally through the heavy nose 2 into the recess 7 thus affording a series of passages, distributed suitably in the mass of the nose 90 2, to communicate with the interior of the plug independently of the central opening 8, 9. I have illustrated four such passages 11 in the present embodiment, but it is of course apparent that any suitable number 95 may be used. The uppermost end of the recess 7 is provided with screw threads which receive a gland 12 similarly threaded as at 13 and engaging therewith for the purpose of assembling said gland into the body 1. 100 Gland 12 carries a central electrode 14 insulated therefrom by a core 15 of mica or other suitable material, and has its extremities projecting to a considerable distance beyond either end of said gland. The lower end 105 of this central electrode, when the gland is properly screwed in place, disposes itself concentrically within the ground electrode ring 10, cooperating therewith to give an infinitely large number of sparking points. 110

Said ground electrode providing as it does a large number of sparking points and being made of round material serves to prevent the accumulation of oil, carbon, and such substances, with the result that the sparking terminals of the plug are maintained clean and effective. The other end of central electrode has a screw threaded portion 16 adapted to receive a nut 17 and thumb screw 18.

10 A jacket 19 of porcelain or the like rests upon the flanged part 20 of the gland 12, being securely held thereupon by means of said nut 17. The flange 20 may be fashioned to receive a suitable tool for tightening said gland in place. A gasket 21 preferably of some yielding material such as copper inserted between said flange and the shell 1 insures a tight joint.

A spark plug made in accordance with my invention finds a very suitable application to engines used for propelling aeroplanes. In aeroplane work the duties imposed and the performance required of the engine are by far more severe and exacting than in the case of engines employed to drive automobiles. In the latter connection the speed and work are variable with seldom an occasion in which the engine is called upon to exert its full capacity for any considerable duration of time. But the conditions subjected to the aeroplane engine are much more stringent, for here the engine is required to ou-
laid its full horse power capacity at a substantially constant speed. At the present time these engines can only be run a short while before it becomes necessary to overhaul and repair them, and experience shows that the spark plug has been a source of considerable trouble and annoyance. These conditions are due largely to the fact that the usual plug, even the recognized standards for automobile engines, are incapable of withstanding the severe heat subjected to them as a result of the continued performance of these aeroplane engines. Where porcelain plugs are used the intense heat generated frequently shatters the porcelain insulator, or in the case of mica plugs the mica often flakes off and becomes sufficiently hot to cause preignition. I have tried out a large number of plugs and am aware that various types and constructions have been used in this class of service. It is also common knowledge that many research laboratories, including those of the United States Government, are constantly endeavoring to acquire means of constructing plugs that will stand up under the conditions above explained. But it is my belief that the construction described and claimed herein is superior to anything heretofore used.

Among the features of my plug that enable me to acquire these necessary ends is the heavy construction of the shell and the communicating passes therein. These orifices,

extending from the recess 7 to the combustion cylinder of the engine afford an avenue whereby the major portion of the hot gases and combustion products may escape from the interior of the plug without coming in contact with and unduly heating or fouling the central electrode. Also by furnishing a ready means of escape of said gases the insulating core 15 is greatly relieved from their deteriorating action. In order to diminish as much as expedient the exposure of the central electrode to the engine gases and at the same time to give additional stock to the nose 2, the opening 9 is made of a diameter sufficient to suitably accommodate the electrode 10. The intermediate recess 8, being made much smaller than recess 7, likewise assists in securing thick heavy walls for the nose portion 2, yet being of somewhat larger diameter than opening 9 removes the liability of short circuit in the event of the presence of carbon or other foreign substances. The heavy walls of nose 2, secured as above explained, being of good heat conducting material serve to convey the heat upwardly and distribute it to the fins 6. Said fins having a large surface area and being exposed to the air readily act to dissipate the heat as fast as it is conducted thereto. Furthermore the passages 11, located in the mass of the shell, furnish heat conducting surfaces whereby much of the heat of the exploding gases is conducted directly to the shell and dissipated by the fins 6. In this way the plug is maintained cool, the heat of the exploding gases not being permitted to accumulate, with injurious effects in the region of the electrode and insulating core.

Another feature to be observed is that the sparking terminals themselves are well exposed to the live gases in the combustion cylinder as in contradistinction to numerous devices employing auxiliary combustion chambers which are apt to become stagnated by burnt gases.

I am aware that the embodiment shown is susceptible to various modifications. For instance, while in the preferred form the recess passing through the nose 2 is made up of two stages 8 and 9, I may provide but one recess having the same diameter as said stage 8 and construct the ground electrode ring 10 accordingly to be supported therein in a manner similar to that shown. Other changes will also suggest themselves to those skilled in the art. However, it is believed that such alterations are within the spirit of the invention and scope of the annexed claims.

Having thus described my invention what I claim is:—

1. A spark plug comprising a body member reduced at one end and externally threaded for the purpose of attachment to 130

- a combustion cylinder, a series of cylindrical recesses of different sizes communicating with each other and arranged consecutively in the order of their diameters to extend 5 throughout the length of said body, a thread cut in the recess at one end of said body and a circular ring arranged in the recess at the other end thereof to serve as a ground electrode, a gland engaged in said threaded 10 recess, a central electrode arranged within said gland but spaced therefrom by means of an insulating core, said central electrode extending centrally through said series of recesses and coöperating with the ground 15 electrode ring, and a plurality of orifices passing through the said reduced portion of the body member to communicate with said threaded recess independently of the other of said recesses and serving as bypasses whereby the major portion of the 20 gases collecting in said threaded recess may escape without coming in contact with the central electrode.
2. A spark plug comprising a body member having a reduced end threaded to its 25 extremity for attachment with a combustion cylinder, said body member having an internally threaded recess at one end and a plain cylindrical recess in said reduced portion but communicating with the first mentioned recess, a gland threaded into the first mentioned recess supporting an insulated 30 central electrode extending into the second mentioned recess and having a gasket member between the head of said gland and said body member, a ring seated in the lower end of said second mentioned recess adjacent the end of said central electrode and serving as a coacting ground electrode, 35 passages in the reduced end of the body member extending from the first mentioned recess to the combustion cylinder at a point closely adjacent the spark gap whereby the gases collecting in the first mentioned recess may 40 escape independent of the second mentioned 45
- recess, said passages also serving as a means for transmitting the heat of said gases to the body member, and heat dissipating means associated with the body member.
3. A spark plug comprising a gland having 50 an insulated central electrode, a body member having a longitudinal opening successively reduced from one end of the body to the other end thereof, said gland supported in one end of said opening and a ground 55 electrode ring supported in the other end, said central electrode being centrally located in said opening and extending to coöperate with the ground electrode ring, said reduced opening serving to secure heavy walls 60 for said body and a plurality of passages located in said walls to communicate with said opening, and heat dissipating fins on said body, said passages serving to lead the combustion products away from the central electrode and the walls of said body 65 serving to conduct the heat to said fins, as described.
4. A spark plug comprising a body member having a heavy nose adapted for engagement with a combustion cylinder, a recess within said body, a circular ring serving as a ground electrode formed and arranged in the end of said recess so as to prevent the accumulation of oils and combustion products, a central electrode located within said 70 recess to coöperate with the ground electrode ring, a plurality of passages located within said nose serving to conduct the combustion gases to and from said recess 75 away from said central electrode thereby preventing the latter from becoming unduly heated, said passages and heavy nose serving also to collect the heat of said gases whereby the same is conducted to the exterior of the body member, and means on the exterior of the body member for dissipating 80 said heat.

In witness whereof I affix my signature.
MAURICE P. SULLIVAN.
